ELECTRIC HEATING ELEMENT

Paul Schwarzkopf, Reutte, Tyrol, Austria, assignor to American Electro Metal Corporation, New York, N. Y., a corporation of Maryland

Application March 9, 1938, Serial No. 194,749
In Germany March 11, 1937

8 Claims. (Cl. 201—64)

This invention relates to electric heating elements for producing high temperatures. Metals having a high melting point, such as molybdenum, tungsten and tantalum, are most suitable for this purpose. Those metals oxidize, however, in the presence of air even at relatively low temperatures between 500° C. and 700° C. and they are therefore to be operated in an atmosphere of reducing or inert gases, or in a vacuum if temperatures of this or considerably higher range are to be produced by them.

In order to utilize the advantages offered by these high melting metals for producing high temperatures in furnaces or for other heating purposes, it has been proposed to cover the resistor proper of a metal of the type referred to above with a ceramic sheathing which reliably and completely prevents the access of gases, particularly of atmospheric oxygen to the metallic resistor core. Such a ceramic sheathing has been obtained by sintering suitable metal oxides having a high melting point which were applied to the core in colloidal form and then fritted or sintered thereon, or a sintered tubular sheathing was shrunk unto the metallic resistor core. Thereby resistor elements of high melting metals but liable to oxidation at relatively low temperature could be used even in open air.

In order to prevent the access of oxygen to the metallic resistor core within the sheathing, it became necessary to apply closures at the ends of the heating elements in such a manner that diffusion of air to the metallic core was prevented. To this effect the ends of the resistor were projected outside the ceramic sheathing and sleeve-like plugs were slipped over the projecting ends and connected with the ends of the ceramic sheathing. However, this plug could not effectively prevent the diffusion of air into the space between the sheathing and the resistor and oxidation of the latter still resulted.

It is an object of the invention to improve end closures for heating elements of the type referred to above in an economical and effective way.

It is a further object of the invention to provide end closures a solid portion of which is converted into dough-like state at operating temperature and thereby assists in gas-tightly sealing the ends of the sheathing to those of the resistor.

It is still another object of the invention to reduce the effect of different temperature expansion of the resistor and its cover.

It is still a further object of the invention

to increase the gas-tightness of the end closures concerned during operation by applying suitable cementing substances between the end closure and the sheathing.

These and other objects of the invention will be more clearly understood when the specification proceeds with reference to the drawing in which by way of example different features of the invention are shown in cross section; for convenience's sake only one end of a heating element is shown in the drawing wherein identical reference numbers indicate parts of similar function.

Referring to Fig. 1, a resistor element 1 in the form of a wire consisting of tungsten, molybdenum, tantalum or another suitable high melting metal of the type referred to above is covered with a ceramic sheathing 2 which extends beyond the end of the resistor 1. Into the projecting end of sheathing 2 the end of a metal pin 3 is inserted which for instance consists of copper. The other end of pin 3 projects beyond the end of sheathing 2, and a sleeve-like plug 4 is slipped thereover. Pin 3 is connected with the resistor 1 in any convenient way, such as by fusion. In order to increase the engaging surfaces of resistor 1 and pin 3 they may be shaped as engaging tongue and groove as shown in Fig. 1.

The feature shown in Fig. 2 differs from that according to Fig. 1 insofar as the engaging surfaces of resistor 1 and pin 3 are wedge-shaped.

Pin 3 may also be made of nickel or an iron-nickel-cobalt alloy.

It will be appreciated that a gas-tight closure between pin 3 and the projecting end of sheathing 2 is obtained thereby that the temperature coefficient of expansion of the metal forming pin 3, for instance that of copper, is higher than that of the ceramic material forming the sheathing so that the copper pin upon heating will be pressed closely against the engaging inner surface of the projecting end of the sheathing. Thereby access of air to the resistor element 1 during operation at high temperatures is effectively prevented. This closing effect can be still further increased by keeping the temperature so high at the place where the pin is connected with the resistor that the portion of the solid metal pin which lies within the projecting end of the ceramic sheathing and contacts the end of the resistor proper, is converted into a state of dough-like plasticity at operating temperatures, and thereby closes the end of the ceramic

sheathing like a glowing metal stopper in a very effective gas-tight manner.

As pointed out above, any metal which is a good heat conductor may be suitably used for the pin, for instance copper, silver, nickel and like metals. For this purpose also an alloy may be used which is a good heat conductor, for instance an iron-nickel-cobalt alloy which at operating temperatures prevailing at the end of the resistor obtains sufficient plasticity so as to bring about a plugging action and to effect gas-tight closure.

It will also be appreciated that upon inserting the heating element in an electrical circuit with the plugs 4 as connecting electrodes, the pin is heated and thereby expands and presses against the inside of the projecting end of the sheathing and if this expanding portion of the pin is rendered plastic or even dough-like, it will closely follow all unavoidable unevenness of the inner surface of the sheathing and tightly fill open spaces, if present, so as to obtain the desired gas-tight plugging effect.

In some cases it may occur, however, that the portion of the pin functioning as a stopper in the way described above is heated locally and suddenly to such a degree that its expansion substantially exceeds that of the adjacent portion of the surrounding end of the ceramic sheathing, whereby the latter may burst, causing rapid destruction of the heating element.

In the feature of the invention shown in Fig. 3 a metal pin is used forming a body composed of a number of parts 3', 3'', 3''' each being of uniform heat conductivity. The conductivities of the parts inter se are, however, different and increase towards the end of the heating element.

Thus the temperatures prevailing at the end of the heating element can be controlled in such a way that the deeper the body forming the pin extends into the end of the ceramic sheathing, the lower is its heat conductivity. As a result, the portions of the projecting end of the sheathing lying close to the end of the heating element will be heated to lower temperatures than portions close to the resistor because outer portions of better heat conductivity of the composite pin will convey away better and faster the heat developed than inner portions of lower heat conductivity, and as a result the temperatures to which the end of the sheathing is heated, is materially reduced and its bursting effectively prevented.

Fig. 3 illustrates the portions of which the pin-like body is composed as of different metals having different heat conductivity in order to obtain the desired effect, to wit, that the heat conductivity of the composite body increases towards the end of the sheathing due to relatively better conductivities of the parts of which it is composed.

According to the feature shown in Fig. 4 the body forming the pin is composed of different parts 3', 3'' and 3''' each of which is of uniform heat conductivity but their individual heat conductivities increase again towards the end of the heating element. To this effect these parts have different diameters, and the diameters increase towards the end of the heating element.

Fig. 4 exemplifies a stepwise increase of the diameters though a gradual increase can be obtained by proper shaping of these parts of the body as will be understood by anyone skilled in the art.

Here again the better conductivity of the parts

of which the pin-like body is composed can be obtained by applying different metals the heat conductivity of which is chosen so that the individual heat conductivities of the parts increase towards the end of the heating element. 5

Instead of or simultaneously with such a choice of metals for the parts of the pin-like body, by enlarging the diameters towards the end of the heating element stepwise or gradually and thereby by the conducting surfaces between the pin-like body and the sheathing, the desired effect of better conducting away the heat towards the end of the sheathing can be effectively obtained.

Care should be taken, however, that the end portions of the pin-like body lying close to the resistor element and thereby nearer the center of the heating element are not heated beyond their liquefying point, in order to prevent undue expansion. To this effect the dimensions of the parts of the pin-like body close to the resistor should be made such that this portion upon heating will not expand to a greater dimension than the internal diameter of the ceramic sheathing. In order to obtain a gradual diminution of the heat developing at the places where adjacent parts of the pin-like body engage each other, those places should be stepped in diameter.

As can be seen from Figs. 1 to 3, a sleeve-like plug 4 is slipped over the end of the pin-like body 3; in Fig. 4 the plug 4 is closed at its outer end.

From the above it will be appreciated that the pin-like body connecting the plug with the resistor element proper is to be dimensioned in such a way that it will be heated at its outer end lying within the plug only to such a low temperature that a tight joint between the plug and the end of the pin-like body lying therein is obtained, whereas the portions of the pin-like body lying within the projecting end of the ceramic sheathing will be locally heated to such an extent that a part or portion thereof becomes plastic or even dough-like for the purpose and to the effect described above.

Also additional means may be used for tightly joining the plug with the end of the sheathing, particularly cements which at temperatures occurring at this joint do not soften at all or at least not beyond the state of dough-like plasticity. Suitable means for this type are in the first place inorganic cements. In particular, metallic cements such as solders containing tin, lead, brass, silver may be applied. Since solders of the metallic type do not adhere sufficiently to ceramic materials it is advisable to metallize the ceramic material at the places to be soldered before the solder is applied.

In addition to the cements mentioned above silver chloride, lead oxide with an addition of glycerine, asbestos-waterglass, quartz-waterglass, soft and hard glasses have been found particularly suitable.

If the heat developed during operation at the places where the cement is to be applied does not exceed temperatures capable of carbonizing organic cements, the latter may also be used. For instance, if the temperatures do not exceed about 200° C., artificial resins may be used as cement.

As may be repeated, it is a condition for the use of any such cement that it either remains solid or reaches only a semi-solid plastic state under the locally occurring temperatures during operation, and that it adheres equally well to ceramic materials and metal and does not react with them to any undesired extent.

It is to be understood that the invention is not limited to any of the particular examples given above but to be derived in its broadest aspects from the claims.

5 I claim:

1. An electric heating element comprising a resistor of metal having a high melting point as exemplified by molybdenum, tungsten and tantalum, a ceramic gas-tight sheathing surrounding 10 said resistor and substantially projecting beyond its ends, pin-like bodies of metal of substantially better electrical conductivity than said high melting metal selected from the group consisting of silver, copper, nickel, iron, cobalt, said bodies 15 snugly fitted into said projecting portions of said sheathing and contacting the ends of said resistor, and a sleeve-like plug fitted upon a portion of each of said bodies outside said sheathing in contact with the latter.

20 2. An electric heating element comprising a resistor of metal having a high melting point as exemplified by molybdenum, tungsten and tantalum, a ceramic gas-tight sheathing surrounding said resistor and substantially projecting beyond its ends, pin-like bodies of metal of substantially better electrical conductivity than said high melting metal snugly fitted into said projecting portions of said sheathing and contacting the ends of said resistor, the portions of said 25 bodies fitted into said projecting portions dimensioned and arranged to contact said ends at places so as to be heated in operation to dough-like plasticity, and a sleeve-like plug fitted upon a portion of each of said bodies outside said 30 sheathing in contact with the latter.

35 3. An electric heating element comprising a resistor of metal having a high melting point as exemplified by molybdenum, tungsten and tantalum, a ceramic gas-tight sheathing surrounding 40 said resistor and substantially projecting beyond its ends, pin-like bodies snugly fitted into said projecting portions of said sheathing and contacting the ends of said resistor, each of said bodies composed of a number, two as minimum, 45 of parts arranged in series within said projecting portions, said parts each of substantially uniform electrical conductivity substantially better than that of said resistor, the conductivities of said parts being different inter se and increasing towards the ends of said sheathing so that the 50 conductivity of said bodies also increases towards said ends, and a sleeve-like plug fitted upon a portion of each of said bodies outside said sheathing in contact with the latter.

55 4. An electric heating element comprising a resistor of metal having a high melting point as exemplified by molybdenum, tungsten and tantalum, a ceramic gas-tight sheathing surrounding 60 said resistor and substantially projecting beyond its ends, pin-like bodies snugly fitted into said projecting portions of said sheathing and contacting the ends of said resistor, each of said bodies composed of a number, two as minimum, 65 of parts arranged in series within said projecting portions, said parts each of substantially uniform electrical conductivity substantially better than that of said resistor, the individual conductivities and the diameters of said parts and thereby the conductivity of said bodies increasing 70 gradually towards the ends of said sheathing, and a sleeve-like plug fitted upon a portion of

each of said bodies outside said sheathing in contact with the latter.

5 5. An electric heating element comprising a resistor of metal having a high melting point as exemplified by molybdenum, tungsten and tantalum, a ceramic gas-tight sheathing surrounding said resistor and substantially projecting beyond its ends, pin-like bodies of metal of substantially better electrical conductivity than said high melting metal snugly fitting into said projecting 10 portions of said sheathing, means for gas-tightly connecting each of said bodies with an end each of said resistor within said projecting portions, said means capable of being heated to dough-like plasticity at operation temperatures, and a 15 sleeve-like plug fitted upon a portion of each of said bodies outside said sheathing in contact with the latter.

20 6. An electric heating element comprising a resistor of metal having a high melting point as exemplified by molybdenum, tungsten and tantalum, a ceramic gas-tight sheathing surrounding said resistor and substantially projecting beyond its ends, pin-like bodies of metal of substantially better electrical conductivity than said high melting metal snugly fitted into said projecting portions of said sheathing and contacting the ends of said resistor, a sleeve-like plug fitted upon a portion of each of said bodies outside 25 said sheathing, and means for gas-tightly connecting said plug with said sheathing, said means capable of being heated to dough-like plasticity at operation temperatures.

30 7. An electric heating element comprising a resistor of metal having a high melting point as exemplified by molybdenum, tungsten and tantalum, a ceramic gas-tight sheathing surrounding said resistor and substantially projecting beyond its ends, pin-like bodies of metal of substantially better electrical conductivity than said high melting metal fitted into said projecting portions of said sheathing and contacting the ends of said resistor, a sleeve-like plug fitted upon a portion of each of said bodies outside said sheathing in contact with the latter, and cementing means for 35 gas-tightly connecting said bodies with said sheathing selected from a group of cementing substances consisting of silver chloride, lead oxide admixed with glycerine, asbestos waterglass, quartz waterglass, soft glass, hard glass, and organic cement including artificial resin.

40 8. An electric heating element comprising a resistor of metal having a high melting point as exemplified by molybdenum, tungsten and tantalum, a ceramic gas-tight sheathing surrounding 45 said resistor and substantially projecting beyond its ends, pin-like bodies of metal of substantially better electrical conductivity than said high melting metal snugly fitted into said projecting portions of said sheathing and contacting the ends of said resistor, a sleeve-like plug fitted upon a portion of each of said bodies outside said sheathing, and cementing means for gas-tightly connecting said plug with said sheathing selected 50 from a group of cementing substances consisting of silver-chloride, lead oxide admixed with glycerine, asbestos waterglass, quartz waterglass, soft glass, hard glass, and organic cement including 55 artificial resin.
